UNITED STATES PATENT OFFICE.

EDWARD W. JOHNSON, OF CHICAGO, ILLINOIS.

AERIAL TORPEDO OR BOMB.

1,396,634.

Specification of Letters Patent.

Patented Nov. 8, 1921.

Application filed November 26, 1917. Serial No. 203,984.

To all whom it may concern:

Be it known that I, EDWARD W. JOHNSON, a citizen of the United States, residing in Chicago, in the county of Cook and State of Illinois, have invented a certain new and useful Improvement in Aerial Torpedoes or Bombs, of which the following is a specification.

This invention pertains to aerial torpedoes or bombs, adapted and designed more particularly to be dropped from an aeroplane, and to explode or discharge when they have traveled through space a given distance.

The main object of the invention is to produce a structure which will be caused to function by its passage through the air, and one which, by reason of its formation, will fall true, or in a straight line.

A further object of the invention is to provide means whereby the bomb may be safely handled and readily set or primed when it is desired to drop the same overboard with a view of having it take its flight of destruction.

With these and other objects and advantages in view, as will appear from the following description, reference will be made to the annexed drawings, wherein;

Figure 1 is a vertical sectional view of the structure, with the parts in proper position to function and produce an explosion when the bomb has traveled a given distance;

Fig. 1^a, a side elevation of the structure;

Fig. 2 a view similar to Fig. 1, showing the operative parts in that relation which they assume when an explosion of the bomb has been effected;

Fig. 3 a perspective view of the device;

Fig. 4 a transverse sectional view, on the line IV—IV of Fig. 5, with one of the hammers and sears removed;

Fig. 5 a vertical sectional view, on the line V—V of Fig. 4, the sear being shown in section;

Fig. 6 a transverse vertical sectional view, on the line VI—VI of Fig. 5, the sear being shown in full and the safety slide present as it is in Figs. 4 and 5;

Fig. 7 a detail sectional view illustrative of a slight modification of the device; and

Fig. 8 a sectional view showing a slightly different arrangement of the lower portion of the bomb.

Referring to the drawings, the structure in general terms may be said to comprise a body having fixed wings or fins which cause

it to maintain its direction during flight without rotation, an explosive-containing chamber with which may be associated various other chambers containing, for instance, projectiles, gas, mustard or other materials, a firing mechanism housed or enclosed within the main body, and a trigger brought into operation through the action of a propeller which partakes of a rotary motion as the structure passes through space during its flight.

In the drawings, 1 denotes a dome-shaped shell or body, having a plurality of radially-disposed vertical wings or fins 2, extending outwardly therefrom, the upper end of the body curving inwardly and terminating in a hub 3. A nut 4 is secured in the hub and a shaft 5 is threaded into the nut, said shaft having secured to its outer upper end a propeller 6. The inner end of the shaft carries a cone-shaped member or trigger 7, which, when the shaft is screwed inwardly, comes into contact with two oppositely-disposed sears 8. Said sears are alike in form and each one is pivotally mounted upon a pin 9 secured in fixed posts or supporting elements 10. The upper inner edge of each sear will preferably be cut away or rounded out, as at 11, Fig. 6, to permit the pointed end of the trigger or actuator 7 to readily pass in between the oppositely-disposed sears and to cause the same to swing free of the notch of the hammers, which latter are denoted by 12. A spring 13 connects the two sears above the line of their pivots and tends to throw the lower ends outwardly and beneath the hammer notches. A spring 14, underlies each hammer, the lower elements of said springs resting upon the upper face 15 of a cylindrical chamber or box-like element, the side walls of which are denoted by 16, and the posts or supporting elements 10 are likewise secured to such upper face. The box-like element or chamber is designed to hold the explosive charge, which may be of any desired material or type, and the lower end of the chamber is closed by a relatively thin disk or partition 17. Said upper wall 15 is provided with two openings 18, and lugs or teats 19 are formed upon the upper face of said wall 15 in line with such openings. The fulminating caps (denoted by 20) are adapted to be placed in such openings 18, and the parts are so proportioned that they directly underlie the striking nose or point of the ham-

mers 12. By providing the lugs or teats 19 one is enabled to more readily place the caps in position though, of course, the presence of these lugs is not essential to the invention.

The explosive-containing chamber is mounted in the upper end of a cylindrical housing or member 21, the upper end of which is threaded, and when the parts are assembled, is screwed into the lower open end of the shell or body 1. Holes or openings 22 are formed in the opposite sides of the cylindrical housing or member 21 in line with the upper faces of the lugs or teats 19, and the hammer-supporting members are likewise notched, as at 23 (Figs. 1 and 2), said notches standing in alinement with the slots or holes 22. A safety slide 24 is adapted to be passed inwardly through the holes 22 and through the notches 23, and to overlie the fulminating caps 20, thereby preventing the hammers from detonating the charge should the bomb be subjected to accidental jar which might throw the sear out of locking relation with the hammers. Thus the device may be readily handled without fear of premature discharge, it being understood, of course, that when the bomb is dropped overboard from an aeroplane or the like the slide will be withdrawn. Said slide is shown in position in Figs. 3 to 6, and is omitted from Figs. 1 and 2.

A projectile-containing chamber is formed in the lower portion of the member 21, and in the preferred form the lower end of this projectile-containing chamber is cone-shaped, as at 25 (see Fig. 1^a). The wall of the chamber may be made of material which will readily disintegrate under the explosive effect of the charge.

Any suitable form of projectile may be employed, but I prefer to use that shown in Fig. 1, which may be said to consist of a bullet-like body 26, having formed upon its rear end a spherical member 27. These projectiles will preferably be buried in some material which will keep them from shifting as, for instance, talc or the like, filled with glycerin, and as shown in Fig. 1, the projectiles will be set at different angles in such substance or body, and when an explosion takes place they will maintain their line of flight in substantially the direction in which they are set within the chamber. This is due to the spherical end upon the rear of the projectile.

An adjusting collar 28 will preferably be placed upon the propeller-shaft 5, which collar may be run downwardly upon the shaft and secured in place to prevent the accidental turning of the shaft inwardly to such a position as would release the sears and cause them to permit the hammers to be thrown downwardly.

In use the cylindrical member 21 is un-

screwed from the shell or body 1, the primers or fulminating caps 20 placed in position, and slide 24 then inserted, the hammers 12, of course, being cocked. The member 21, with the contained explosive charge and the projectile charge therein, will then be screwed back into the shell or casing 1, and the collar 28 likewise screwed down upon the shaft to prevent the same from being turned inwardly and accidentally releasing the sears. With the parts in this position the bomb may be readily handled without fear of explosion. When, however, it is desired to have the parts placed in operative relation, the collar 28 is turned backwardly and the slide 24 withdrawn. Then, upon dropping the bomb overboard, it will take a downward flight, being guided by the wings or vanes 2, and dropping straight. The shaft 5 will be rotated by the action of the air impinging directly against the blades of the propeller 6, the air striking such blades directly by reason of its passing upwardly between the wings 2. This rotation will cause the shaft to turn inwardly and eventually to bring the parts to the positions shown in Fig. 2, where the sears will be withdrawn from the hammer-notches, and the hammers thrown forwardly and into contact with the caps or fulminating charge 20, thereby causing an explosion of the charge within the chamber directly underlying the caps. Such explosion will disrupt the relatively thin disk 17 and likewise the projectile-containing chamber, throwing the projectiles and the parts of the casing in all directions.

The length of the interval between the time when the projectile is dropped and the moment of explosion may be determined by the position of the trigger or actuating member 7; that is to say, whether it has to travel a greater or less distance before it impinges upon and releases the sears 8, and the user of the bomb can readily determine this by screwing the shaft in or out to a greater or less extent. Naturally, if the actuator 7 stands a considerable distance from the sears the shaft will have to make a greater number of revolutions before it contacts with the sears than would be the case if the actuator stood close to the sears.

While the device would, of course, function with but one hammer, two are employed as a factor of safety, for the reason that it sometimes happens that the caps are defective, but it is scarcely conceivable that both caps (where two are present) would fail to function.

In Fig. 7 there is shown a modification of the structure, wherein the hammer mechanism, as such, is omitted and the propeller-carrying shaft acts, when moved inwardly to a predetermined extent, to effect the functioning of the detonator.

- In said figure the shell or casing 1 is provided with wings 2, as under the other construction, and the propeller and shaft are also present. The shaft, however, is provided with a short threaded section only, and a spring 29 surrounds the same, bearing at one end on the upper face of the cone-shaped member 7 and at its opposite end against the under face of the nut 4.
- 10 The upper face of the explosive-containing chamber is provided with a single opening, and that to receive a detonating cap, which stands in axial alinement with the shaft and head or member 7, which in effect becomes a hammer or striker to detonate the cap. As will be readily appreciated, when the shaft is screwed in by the action of the propeller so that the threads thereon clear the inner end of the nut, the spring 29, which is still 15 under compression, will drive the point of the head or member 7 into contact with the cap and detonate the same.
- Such short thread and spring arrangement may also be employed with the sear 25 and hammer mechanism above described, in which event the head 7 will strike the sears and release the same. This arrangement being obvious, I have not deemed it necessary to illustrate the same.
- 30 In Fig. 8 a still further modification is illustrated wherein the conical chamber at the lower end of the structure is employed as a container for gas, inflammable oil, or the like. The explosion of the charge will 35 cause both of the chambers to become effective, to wit, those containing the projectiles and the oil, gas or mustard.
- It is to be noted in connection with this invention that the structure will function 40 without contact with any object, and that the full force of the explosion is thereby utilized, which is not the case where the contact of the bomb with the earth is depended upon, much of the explosive force 45 being wasted under such arrangements.
- Having thus described my invention, what I claim is:
1. A bomb comprising in combination, a hollow body; a nut mounted in the upper 50 end thereof; a plurality of longitudinally-extending, radially-disposed wings projecting outwardly from the body; a chamber
- detachably secured to the lower end of the body and adapted to contain an explosive charge and a plurality of projectiles; a screw-threaded shaft mounted in the nut; a propeller secured to the outer end of the shaft; a hammer located above the chamber; and a sear for the hammer, said sear standing in the path of movement of the shaft and adapted to be released thereby when the shaft is moved inwardly under the action of the propeller, whereby the hammer will be likewise released and cause an explosion of the charge. 65
2. A bomb comprising, in combination, a hollow body; a plurality of longitudinally-extending, radially-disposed wings projecting outwardly therefrom; a screw-threaded shaft mounted to rotate in the upper end of the body and in axial alinement therewith; a propeller mounted on the upper end of the shaft; a cone-shaped member secured to the inner end of the shaft; an explosive and projectile-containing chamber detachably secured to the lower end of the hollow body, 70 said chamber having two openings extending through its upper wall and over which detonating caps are designed to be placed; a pair of oppositely-disposed, spring-actuated hammers arranged adjacent said openings; and a sear for each hammer, said sears, when in holding relation with the hammers, standing in the path of movement of the cone-shaped member aforesaid and adapted 75 to be released thereby when the shaft is moved inwardly under the action of the propeller.
3. A bomb comprising a body, a plurality of wings extending radially therefrom; a threaded shaft mounted in the upper portion of the body; a propeller secured to the outer end of the shaft; an explosive and projectile-containing chamber secured to the body; a firing mechanism embodying a pair 90 of spring actuated hammers and a sear for each hammer arranged above the chamber, said sears being adapted to be released by the shaft as it is moved inwardly; and a removable safety slide underlying the firing 95 mechanism.
- In testimony whereof, I have signed my name to this specification.
- EDWARD W. JOHNSON.
